UNITED STATES PATENT OFFICE.

FAIRFAX H. WHEELAN AND ALBERT SCHURCH, OF SAN FRANCISCO, CAL.,
ASSIGNORS OF ONE FOURTH TO LOUIS CHRISTIN, OF SAME PLACE.

CHROMATIC-PRINTING APPARATUS.

SPECIFICATION forming part of Letters Patent No. 360,185, dated March 29, 1887.

Application filed August 31, 1885. Serial No. 175,857. (No model.)

To all whom it may concern:

Be it known that we, FAIRFAX H. WHEELAN and ALBERT SCHURCH, both of the city and county of San Francisco, State of California, have invented an Improvement in Chromatic-Printing Apparatus; and we hereby declare the following to be a full, clear, and exact description of the same.

Our invention relates to certain improvements in chromatic printing, so that two or more colors may be printed at one impression.

It consists in the construction and combination of devices, all of which we shall hereinafter fully describe.

The object of our invention is to provide a practical apparatus for printing in two or more colors.

Referring to the accompanying drawings, Figure 1 is a longitudinal vertical section of a portion of our apparatus, showing a part of the impression-roller, the distributing-rollers, and inking-pad for one set of type or surfaces, the other set of type or surfaces, its inking-roller, and means for operating it. Fig. 2 is a plan view of the inking apparatus for the type-surface D, showing the frames M and W in section. Fig. 3 is a plan view of the mechanism illustrated in Fig. 1, and showing portions of the frames M and W broken away. Fig. 4 is a detail showing the frames M P W and connections.

A is the impression-roller of a printing-press.

B B are rollers which are used for distributing and applying any color of ink to a fixed set of type, B', which are the usual type of the ordinary form.

C is the ink-distributing table, which reciprocates in order to receive ink from the inking-roller (not here shown) and to carry it to the distributing-rollers B.

D represents the type or surfaces which are to print the second color, the type which print the primary color being the ordinary type heretofore mentioned. The type D are fixed in the reciprocating bed and move with it.

It is necessary that the type D should be inked before passing under the impression-roller, and should be moved out of the way while passing beneath the rollers B of the first

set of type, and again raised to place after passing these rollers, so as to present their surfaces to the impression-roller.

In Fig. 1 is shown the bed or block X for the type D, which are on a frame, X', having corrugated under surface, or furnished with alternate elevations and depressions, as shown at E, and these move over similar elevations or depressions, F, on a plate, X", in the base or bed X. When the elevations E and F are brought in vertical line, the elevations E, resting on top of those at F, will raise the type-surface so that it is possible to receive ink or give an impression; but when the elevations E fall into the depressions between F the type will be depressed below the level of the inking-rollers. In order to produce this alternate elevation and depression of the type, the plate X" of the elevations F is so mounted in the bed X as to be reciprocated slightly therein, and said frame is connected by a rod, G, to a crank-pin, g, on a drum or cylinder, H, mounted in one end of the bed, so that when said cylinder is oscillated it will cause the frame of the elevations F to be reciprocated, thus raising or lowering the type D, as heretofore described.

In order to move the elevations F at the proper time, the pins I are fixed in the end of the drum H, and these pins, as they move against suitable arms or lugs placed at proper points, will be struck and cause the drum H to oscillate for the purpose described. But before the type D are depressed they should be inked. This is accomplished as follows: To the side of a fixed main frame, M, is secured a frame, W, which is provided with small anti-friction rollers w, fitted in a vertical slot in said frame M. P is another frame, which is slotted and travels vertically on small rollers p, secured to frame W. Journalled on a shaft, q, passing through the frame P is the inking-roller Q. Pivoted to the frame W is a bell-crank lever, L, the lower end of which carries a roller, N. The upper end of the lever L comes in contact with the lower arm of a pivoted bell-crank lever, O, the pivot-shaft of which passes through the frames W and M, and said lever is influenced to remain in position by means of a spring, o'. The other or horizontal arm of the lever O is pivoted to the

frame P at o^2 . The lever L is limited in its movement by the fixed stop l.

The operation so far as explained is as follows: The type-bed X has on its side a track, 5 d'. As the type D pass forward this track comes in contact with the roller N, whereby the lever L is moved so that its upper arm comes in contact with the lower arm of the lever O, the horizontal arm of which is thus depressed, causing the frame P to move down, so that the inking-roller Q is forced into contact with the type D. To the frame W is secured the arm J, which comes in contact with the pin I of the drum H, whereby it causes a 10 partial rotation of said drum, so that through the pitman G the elevations F are moved to allow the projections E of the type-frame X' to fall into the intervening depressions, so that the surface of said type is depressed in order 15 to avoid the distributing-rollers B. It is also necessary that the inking-pad C should avoid the inking-roller Q. Accordingly we have the following mechanism: Journaled in the end of a bell-crank lever, S, is a large wheel, R, having a cushioned surface, r. The lever S is 20 pivoted on a shaft, T, to the main frame M, and is connected by a link, U, with a bell-crank lever, V, pivoted on a shaft, X', which 25 passes through the main frame M. The other arm of the lever V is pivoted to the frame W. The lever S is held in its position by means of a pivoted arm, s', influenced by a spring, s'', and connected with the lever S by a link, s. As the inking-pad C moves forward it first 30 comes in contact with the cushioned wheel R and raises said wheel, whereby, through the levers S and V and the link U, the whole frame W is raised slightly, and as said frame carries the frame P, in which the inking-roller Q 35 is mounted, it will be seen that said roller is thus raised above the inking-pad, so that it does not come in contact with said pad. As the arm J is secured to the vertically-adjustable frame W it will rise as it comes in contact 40 with the track d' on the type-bed X, and will therefore not interfere with the passage of said bed.

When the type D, depressed, as heretofore described, to avoid the distributing-roils B, 45 have passed said rolls and are about to pass under the impression-cylinder A, it is necessary that said type shall be raised again to position. This is accomplished by the arm K, which, as in the case of the arm J, comes 50 in contact with the uppermost of the pins I of the drum H in the bed of type D. Thus just before the type D pass under the cylinder they are elevated to position, and consequently 55 make their impression. But it is also necessary that the arm K shall not be in the way of the inking-table C. To avoid this we secure 60 the arm K to one end of a series of levers, Y, pivoted to one another, and carrying a roller, Z, with which the table C comes in contact 65 and raises it, whereby the arm K is also raised out of the way.

Having thus described our invention, what

we claim as new, and desire to secure by Letters Patent, is—

1. In a chromatic-printing press in which two or more colors are employed, a means comprising an oscillatory drum and a reciprocating plate operated thereby for depressing one set of type-surfaces below the level of the remaining type, so that the latter may be inked independently of the former, substantially as herein described. 70

2. In a chromatic-printing apparatus, the type-surface D, adapted to be depressed or raised, in combination with a drum upon the type-bed and lugs or projections which engage pins upon the drum, so as to partially rotate it, and through it cause the type to be depressed or to be elevated, substantially as herein described. 75
